(57) **ABSTRACT**

A Chrysanthemum plant named 'Zanmurateous' characterized by its medium sized blooms with orange red ray florets and prolific branching; natural season flowering date September 19 (week 38); blooming for a period of 4 weeks.

3 Drawing Sheets

1

Botanical designation: *Chrysanthemum×morifolium* Ramat.
Cultivar denomination: 'Zanmurateous'.

BACKGROUND OF THE INVENTION

The present invention relates to a new and distinct cultivar of *Chrysanthemum* plant, botanically known as *Chrysanthemum×morifolium* Ramat., commercially known as a garden mum, and hereinafter referred to by the cultivar denomination 'Zanmurateous'. 'Zanmurateous' is a product of a breeding and selection program for outdoor pot mums (garden mums) which had the objective of creating new cultivars with a double type inflorescence, a natural season flowering date around September 19 (week 38), blooming for a period of 4 weeks. 'Zanmurateous' is a seedling resulting from a cross of the female parent id 24610 with the male parent id 22135. Plants of the new cultivar 'Zanmurateous' differ from plants of the female parent in the color of the ray-florets; the ray-florets of the female parent are red, while those of the seedling are orange. Plants of the new cultivar 'Zanmurateous' differ from plants of the male parent in the following characteristics. (1) Color ray-florets. And (2) Plant vigor. (1). Ray-florets of the male parent are more deeply orange colored than those of the seedling. (2). Plants of the male parent are less vigorous than those of the seedling.

The new and distinct cultivar was discovered and selected as a flowering plant by Wilhelmus Bernardus Blom on a cultivated field in Rijsenhout, The Netherlands in 2006. The first act of asexual production of 'Zanmurateous' was accomplished when vegetative cuttings from the initial selection in 2006 were propagated further in a controlled environment in Rijsenhout, The Netherlands. The new cultivar has been found to retain its distinctive characteristics through successive propagations.

BRIEF DESCRIPTION OF THE DRAWINGS

The present invention of a new and distinct variety of *Chrysanthemum* (of about 17 weeks) is shown in the accom-

2

panying drawings, the color being as nearly true as possible with color photographs of this type.

FIG. 1 shows a plant of the cultivar in full bloom.

FIG. 2 shows the various stages of bloom of the new cultivar.

FIG. 3 shows the various stages of foliage of the new cultivar.

DESCRIPTION OF THE INVENTION

10 The observations and measurements were gathered from plants grown out door in Rijsenhout, The Netherlands under natural day length and temperature and planted in week 22 in 2011. The natural blooming date of this crop was September 15 19 (week 38). The average height of the plants was 30 cm. No growth retardants were used. No tests were done on disease or 20 insect resistance or susceptibility. No tests were done on cold or drought tolerance. This new variety produces medium sized blooms with orange red ray florets blooming for a period of 4 weeks.

25 From the cultivars known to inventor the most similar existing cultivar in comparison to 'Zanmurateous' is 'Zanmutomic' (U.S. Plant Pat. No. 21,183). When 'Zanmutomic' and 'Zanmurateous' are being compared the following differences are noticed: (1) Number ray-florets. And (2) Color ray-florets. (1) The number of ray-florets is lower in 'Zanmutomic' than in 'Zanmurateous'. (2) The orange colored ray-florets are more reddish in 'Zanmurateous' than in 'Zanmutomic'.

30 The following is a description of the plant and characteristics that distinguish 'Zanmurateous' as a new and distinct variety.

The color designations are taken from the plant itself. Accordingly, any discrepancies between the color designations and the colors depicted in the photographs are due to photographic tolerances. The color chart used in this description is: The Royal Horticultural Society Colour Chart, edition 2001.

TABLE 1

Botanical Description of <i>Chrysanthemum x morifolium</i> Ramat. 'Zanmurateous'	
<u>Bud</u>	
Size:	Small; cross-section 6 mm, height 5 mm
Shape:	Round
Texture:	Pubescent
Outside color:	Greyed-green 191A
Phyllaries	
Number:	24, arranged in 3 rows
Shape:	Elliptic
Apex:	Acute
Base:	Truncate
Margin:	Entire
Color:	Upper side: Green 138A Lower side: Green 137A
Length and width:	8 mm; 2 mm
Texture:	Pubescent
Inflorescences	
Type:	Double
Height:	2.5 cm
Diameter:	5.5 cm
Peduncle length:	4-7 cm
Peduncle color:	Greyed-green 191A
Peduncle diameter:	1.5-2 mm
Peduncle texture:	Pubescent
Number per branch:	Approx. 7 inflorescences
Duration of flowering:	4 weeks
Seeds:	Produced in small quantities, ovate, Greyed-brown 199A, length 1.5 mm, diameter 0.5 mm
Fragrance:	Faint <i>chrysanthemum</i> odor
Color	
Center of inflorescence:	Immature stage: Greyed-red 178A; Mature stage: Greyed-red 178B
Color of upper side of ray florets:	Greyed-red 179B
Color of lower side of ray florets:	Greyed-orange 175D
Tonality from distance:	A garden mum with orange red blooms
Color of ray florets after aging of the plant:	Greyed-orange N170B
Ray florets	
Texture:	Upper and lower side smooth
Number:	250-260
Shape:	Elliptic
Apex:	Pointed to Dentate
Base:	Attenuate
Cross-section:	Concave
Longitudinal axis:	Incurving
Length of corolla tube:	5 mm
Ray floret margin:	Entire
Ray floret length:	2-2.2 cm
Ray floret width:	2.5 mm
Ratio length/width:	High
Disc florets	Absent
Receptacle	
Color:	Yellow-green 145D
Shape:	Conical raised
Height:	7 mm
Diameter:	5 mm
Reproductive Organs	
Androecium:	Absent
Gynoecium:	Present in ray florets
Style color:	Yellow-green 154C
Style length:	3 mm
Stigma color:	Yellow 7A

TABLE 1-continued

Botanical Description of <i>Chrysanthemum x morifolium</i> Ramat. 'Zanmurateous'	
5	Stigma width: 1 mm Ovary: Enclosed in calyx Plant
10	Form: Grown as a spray type pot <i>mum</i> , outdoor raised and mounded Growth habit: Spherical shape Growth rate: Medium Height: 30 cm Width: 40-50 cm Stem color: Greyed-brown 199A Stem strength: Strong Stem brittleness: Not brittle Stem anthocyanin: Not observed coloration:
15	Internode length: 3 cm Length of lateral branch: From top to bottom 18-20 cm Lateral branch color: Green 137 C Lateral branch, attachment: Brittle Lateral branch diameter: 3-4 mm Branching (average number of lateral branches): Prolific with 8 breaks after pinching Natural season blooming date: September 19 (week 38-41) Foliation
20	Leaf color: Upper side: Green 137A; Lower side: Green 138A Color midvein: Upper side: Yellow-green 147D; Lower side: Yellow-green 148D Size: Small; length 4-7 cm, width 2-3.5 cm Quantity (number per lateral branches): 14-16
25	Shape: Elliptic Texture upper side: Sparsely pubescent Texture under side: Pubescent Venation arrangement: Palmate Shape of margin: Serrated Shape of base of sinus between lateral lobes: Rounded Margin of sinus between lateral lobes: Diverging Shape of base: Attenuate to truncate Apex: Mucronulate Petiole length: 1-2.5 cm Petiole diameter: 1.5 mm Petiole color: Yellow-green 147D
30	
35	
40	
45	
50	Differences with the comparison variety (when grown under identical conditions)
	'Zanmurateous' 'Zanmutomic'
55	Number ray-florets 250-260 130 Color upper side ray-florets Greyed-red 179B Greyed-orange 172A

I claim:

1. A new and distinct *Chrysanthemum* plant named 'Zanmurateous' as described and illustrated.
